UNITED STATES PATENT OFFICE.

GEORGE S. CARTER, OF LEWISBURG, PENNSYLVANIA, ASSIGNOR OF ONE-HALF HIS RIGHT TO WILLIAM HAUCK, OF SAME PLACE.

IMPROVEMENT IN GRAIN-CLEANER AND SEPARATOR.

Specification forming part of Letters Patent No. 122,436, dated January 2, 1872.

To all whom it may concern:

Be it known that I, GEORGE S. CARTER, of Lewisburg, in the county of Union and State of Pennsylvania, have invented a new and valuable Improvement in Grain-Cleaners; and I do hereby declare that the following is a full, clear, and exact description of the construction and operation of the same, reference being had to the annexed drawing making a part of this specification, and to the letters and figures of reference marked thereon.

Figure 1 of the drawing is a representation of a vertical longitudinal section of my invention. Fig. 2 is an under-side plan view.

This invention has relation to grain-cleaners; and the novelty consists in the construction and improved arrangement of devices for the purpose of vibrating the grain-screens, as hereinafter described.

In the accompanying drawing is shown the body and frame-work A of a grain-cleaning machine, supporting all the other parts. B represents the hopper, through which the grain is conveyed to the screens. C is an inclined floor, upon which the grain falls from the hopper and passes thence to the first screen D, which is inclosed within the laterally vibrating screen-frame D'. The floor C is also inclosed within or attached to the screen-frame D', which is pivoted to the top of the case A, near its forward end, as shown at a, and supported at its rear end by means of hinge-rods a'. E designates the fan-box, inclosing the rotary fan E¹, journaled transversely, the ends of its shaft E² projecting beyond the sides of the case A. On one end of said shaft is placed a pinion, e, which engages with a spur-wheel, e¹, journaled to the upper part of the case A, and operated by means of a crank-arm, e², attached to its shaft e³. The opposite end of the shaft E² is armed with a crank, e⁴, holding one end of a pitman, F, the other end of which is pivoted to a bell-crank, F', pivoted by means of a vertical pin between two brackets, f, projecting from the side of the case A, or arranged in any other suitable manner. To one arm of this bell-crank is attached a rod, f', which passes through the side of the case A, and is connected to the side of the screen-frame D'. Hence, when the fan is rotated a lateral vibra-

tion is given to the screen-frame. G indicates a longitudinally-vibrating or reciprocating screen-frame, provided with a screen, H, and arranged underneath the screen-frame D' in such a relation to it that the grain which falls from the floor d of said screen-frame D' shall fall on the screen H. The frames G and D' may be provided with any desirable number of screens of different kinds to separate the grain into its different qualities, &c. After being screened by the screens in the frame G the particles are conveyed through the chutes or spouts g and opening g' to the several apartments of the bin h. I indicates a transverse shaft, having spindles which pass through the sides of the case A. One of these spindles holds an arm, I¹, which is pivoted to a bar, I², one end of which is attached to the crank e⁴. Hence, when the fan rotates a rocking motion is given to the shaft I. This shaft has hinged to its lower side a bar, J, which extends lengthwise of the case A, underneath the floor of the screen-frame G, to which it is secured. By means of this bar a reciprocating motion is given to the screen-frame G by the rocking of the shaft I. The rear end of the screen-frame G is supported to the case A by means of a hinged arm or stirrup, k, on either side.

The arms of the bell-crank F' and the arm I¹ are perforated, so that their connections may be adjusted to vary the motions of the screen-frames.

I claim as my invention—

1. The combination of the reciprocating screen-frame G, hinged rod J, rock-shaft I, arm I¹, rod I², crank e⁴, and rotary shaft E², constructed and arranged substantially as and for the purpose specified.

2. The laterally-vibrating screen-frame D', bell-crank F', pitman F, rod I², rock-shaft I, and reciprocating screen-frame G, combined and operating substantially as set forth.

In testimony that I claim the above I have hereunto subscribed my name in the presence of two witnesses.

GEORGE S. CARTER.
